BEVERAGE VENDING MACHINE

Eliot Noyes, New Canaan, Conn., assignor to Westinghouse Electric Corporation, East Pittsburgh, Pa., a corporation of Pennsylvania

Filed Sept. 14, 1964, Ser. No. 81,701

Term of patent 14 years

(Cl. D52—3)

The figure is a perspective view of a beverage vending machine, showing my new design. The opposite side of the beverage vending machine is substantially the same in appearance as the side shown, and the rear is unadorned.

The dominant features of the design reside in the portions shown in solid lines.

I claim:

The ornamental design for a beverage vending machine, substantially as shown and described.
